(57) CLAIM

The ornamental design for a window trim clip, as shown and described.

DESCRIPTION

FIG. 1 is a rear isometric view of a window trim clip of my new design;

FIG. 2 is a rear view thereof;

FIG. 3 is a front view thereof;

FIG. 4 is a bottom view thereof;

FIG. 5 is a top view thereof;

FIG. 6 is a first side view thereof;

FIG. 7 is a second side view thereof;

FIG. 8 is a perspective view thereof; and,

FIG. 9 is a cross-sectional view along line 9-9 of FIG. 8. The shading on the window trim clip is meant to delineate contour, not material or surface texture.

The window trim clip is shown with symbolic breaks in its length and width. The appearance of any portion of the window trim clip between the break lines forms no part of the claimed design.

The broken lines showing the window, the window cover, and portions of the vehicle are for environmental purposes only and form no part of the claimed design.

The dot-dash lines are for the purpose of showing the boundaries of the claimed design and form no part thereof.
